(57) **CLAIM**

The ornamental design for an electronic article surveillance apparatus, as shown and described.

DESCRIPTION

FIG. 1 is a top perspective view of an electronic article surveillance apparatus in an assembled state having a symmetrical composition.

FIG. 2 is a perspective view from the bottom of the apparatus in an exploded state.

FIG. 3 is an interior view of the top of the apparatus in an unengaged state.

FIG. 4 is an interior view of the bottom of the apparatus in an unengaged state.

FIG. 5 is a left side plan view of the apparatus in an engaged state.

FIG. 6 is a right side plan view of the apparatus in an engaged state.

FIG. 7 is a top plan view of the apparatus in an engaged state; and,

FIG. 8 is a bottom plan view of the apparatus in an engaged state.

The top and bottom portions have been shown separately in FIGS. 3 and 4 for convenience of illustration.
